UNITED STATES PATENT OFFICE.

GEORGE ADAM HESS, OF MAQUOKETA, IOWA.

GATE.

SPECIFICATION forming part of Letters Patent No. 497,663, dated May 16, 1893.

Application filed December 9, 1892. Serial No. 454,631. (No model.)

To all whom it may concern:

Be it known that I, GEORGE ADAM HESS, a citizen of the United States, and a resident of Maquoketa, in the county of Jackson and State of Iowa, have invented certain new and useful Improvements in Gates; and I do hereby declare that the following is a full, clear, and exact description of the invention, which will enable others skilled in the art to which it appertains to make and use the same, reference being had to the accompanying drawings, which form a part of this specification.

My invention relates to improvements in swinging gates of that character or description in which the horizontal slats are pivoted to the upright hinged or pivoted to the gate post, said upright being provided with a counterbalance weight connected by means of a rod or bar with the uprights which engage with the opposite gate post.

The object of my invention is to provide an improved construction of swinging gate which shall possess superior advantages with respect to efficiency in operation.

The invention consists in the novel construction and combination of parts herein-after fully described and claimed.

In the accompanying drawings: Figure 1 represents a perspective view of a gate constructed according to my invention. Fig. 2 is a plan view of the same. Fig. 3 is an elevation.

In the said drawings the reference numerals 1 and 2 designate the gate posts, which may be of any suitable construction. The front gate post 1 is provided with aligned pins 3 near the top and bottom, with which the front uprights of the gate engage when the latter is closed.

The gate consists of a series of horizontal slats 4, the ends of which are embraced by the uprights 5, to which said slats are pivoted. The numeral 6 denotes the rear uprights, similar to the uprights 5, except that they are longer and extend some distance above the top slat 4. These uprights 6 are connected together and are pivoted or hinged to the gate post 2. Near the upper ends of these uprights 6 are pivoted arms 7, to the free ends of which is secured a rectangular box or receptacle 8, for con-

taining a counterbalancing weight of any suitable material. These arms are provided with a cross bar 9, with which is connected a rod or bar 10, the other end of which is connected with the front uprights 5.

The operation will be readily understood. A proper weight is placed in the receptacle 8, which will tend to counterbalance the gate so as to allow the front end to be readily lifted to disengage the uprights from the pins to allow the gate to be swung open. The weight is secured to the receptacle in any manner so that it may be readily removed and replaced, and varying weights may also be used so as to require more or less power to operate the gate according as it is required when the same lifts easy or hard.

A latch may be employed in connection with the gate, and instead of the pins 3, cleats 12 may be substituted therefor as seen in Figs. 2 and 3.

From the above it will be seen that I provide a gate which can be so counterbalanced as to work very easy if desired, and by varying the weights in the receptacle or removing them altogether, the gate will work very hard or require considerable power to raise the same to swing it open which will be found very advantageous under certain conditions or circumstances.

Having thus described my invention, what I claim is—

In a swinging gate, the combination with the gate posts, and the gate consisting of the rear uprights pivoted to one of said posts, the front uprights and the horizontal rails pivoted to said uprights, of the arms pivoted to the rear uprights, the weight secured to the upper ends of said arms, the cross bar secured to said arms intermediate their ends, and the inclined bar connected with said cross bar and pivotally connected with the front uprights, substantially as described.

In testimony that I claim the foregoing as my own I have hereunto affixed my signature in presence of two witnesses.

GEORGE ADAM HESS.
